(57) **CLAIM**

The ornamental design for pants, as shown and described.

DESCRIPTION

FIG. 1 is a perspective top front left view of a pair of pants, showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The dotted lines, as opposed to the broken lines, in FIGS. 1-7 designate stitching which is part of the claimed design. The broken lines shown in FIGS. 1-7, illustrate environment and form no part of the claimed design.

1 Claim, 5 Drawing Sheets

FIG. 1

FIG. 2
